UNITED STATES PATENT OFFICE.

LANSING ONDERDONK, OF NEW YORK, N. Y., ASSIGNOR TO UNION SPECIAL SEWING MACHINE CO., OF CHICAGO, ILLINOIS, A CORPORATION OF ILLINOIS.

CHAIN-STITCH SEWING-MACHINE.

No. 839,077.

Specification of Letters Patent.

Patented Dec. 18, 1906.

Application filed May 21, 1901. Serial No. 61,272.

To all whom it may concern:

Be it known that I, LANSING ONDERDONK, a citizen of the United States, residing at New York, in the county of New York, State of New York, have invented certain new and useful Improvements in Chain-Stitch Sewing-Machines, of which the following is a description, reference being had to the accompanying drawings and to the letters of reference marked thereon.

My invention relates to an improvement in sewing-machines, and particularly to machines of that class known as "horn-machines," in which the work is placed over a horn or cylindrical bed-plate containing a feeding mechanism working longitudinally thereof, although so far as certain features of the invention are concerned it is not limited to the use of a cylindrical bed-plate, but is of scope sufficient to include "post-machines," where the bed-plate is in the form of a post.

The main object of the present invention is to provide a machine having improved means for driving the feeding and looper mechanisms.

Another object is to provide a machine of the type referred to in which the work shall be fed off the horn or bed-plate instead of on to the same, as is usual in machines in which the feed works longitudinally of the bed-plate.

The present machine is designed particularly for sewing the overlapped longitudinal edges of tubularly-arranged work, such as the legs of trousers, overalls, or the like or the sleeves or bodies of shirts, &c., the bed-plate being so arranged that the work is fed off the same, the rear end being arranged at the front of the machine and adjacent the operator and the framework of the machine being so constructed as to leave an uninterrupted space in which the hands of the operator may work to properly manipulate the material to be sewed.

The invention consists in the various matters, all as hereinafter described and referred to in the appended claims.

The invention is illustrated in the accompanying drawings, in which—

Figure 1 is a perspective view of my improved machine. Fig. 2 is a plan with the cover-plates, end cap, and gooseneck removed. Fig. 3 is a side elevation, the tubu-

lar bed-plate being in longitudinal vertical section. Fig. 4 is a transverse vertical section on line 4-4 of Fig. 3, the cover of the post being removed. Fig. 5 is a front elevation of the main feed-bar-operating lever. Figs. 6 and 7 are front and side elevations of an auxiliary feed-bar-operating lever. Fig. 8 shows the eccentrics for actuating said two levers. Fig. 8^a is a face view of the larger eccentric, showing the wrist-pin and its ring. Fig. 9 is a detail view in perspective of the feed and looper operating devices, the space separating the two mechanisms being exaggerated.

The machine-frame comprises a hollow horizontal angular casing A, from the rear end of the member A' of which rises the gooseneck B, which lies at right angles to the said case member A' and parallel with the forward case member A². At the left-hand end of the case member A² rises the hollow post A³, from the upper end of which projects the rearwardly-extending cylindrical bed-plate or horn A⁴, parallel with the case member A', but in a higher plane. The rear end of the bed-plate A⁴ has a removable end cap A⁵, which incloses the two loopers and the feed-dog to be presently described.

The upper tension mechanism, the needle-bar N, its needle-carrier n, and operating-lever N', the presser-foot P, and the presser-foot bar P' are all of the usual construction and need not be described.

The horizontal drive-shaft C is mounted in bearings in the frame at the rear end of the member A' and base of gooseneck B and has two cranks c c, to which are connected the rear ends of the connecting-rods C' C', which extend forwardly through the case member A' to the two cranks d d on the right-hand end of the line-shaft D, mounted in bearings d' in the front case member A². These different members of the frame-casing are provided with removable covers a', a², and a⁴ in order that the concealed parts may be cleaned, oiled, &c.

The left-hand end of the line or driven shaft D is within the lower end of post A³ provided with two eccentrics d² d³, and the former carries a wrist-pin d⁴ in the form of a ball.

F designates the four-motion feed-bar, mounted in bearing blocks or guideways f f

within the top of the cylindrical bed-plate A⁴ and carrying at its rear end the feed-dog F', the work being fed off of the cylindrical bed-plate or horn. The feed-bar F is pivotally connected at its rear or far end to vertically-disposed links f' f', pivoted at their lower ends in the lower portion of the bed-plate or horn A⁴, and the near or front end of the feed-bar—that is, the end nearest the operator—is pivotally connected to the upper forked end f² of the main lever F², the lower end of said lever being strapped to the larger eccentric d² on shaft D. The lever F² is further acted upon by the auxiliary lever F³, forked at its lower end f⁴ to straddle the smaller eccentric d³ of shaft D and split thereabove, as at f¹⁰, and having a tightening-screw f¹¹ to regulate the space between the fork. This lever F³ is pivoted at its upper end to the right side of the lever F² by a pivot-screw f³, (shown in dotted lines, Fig. 3,) and the lever F³ is further provided between its ends with a longitudinal fulcrum-slot f⁵, through which passes the enlarged rounded portion of the fulcrum-bolt f⁶, having a flattened threaded end mounted adjustably in an inclined vertically-disposed slot a⁸ in the post A³. (See Fig. 4.) By adjusting this bolt f⁶ the throw of the feed-bar 30 may be lengthened or shortened to vary the stitch. It will be seen that the main lever F² effects the raising and lowering of the front end of the feed-bar and also raises the lever F³ and that in the further rotation of the eccentric d² d³ the auxiliary lever F³ will be rocked on its axis f⁶, so as to rock the main lever and impart the necessary longitudinal movement to the feed-bar F. The auxiliary lever F³ therefore forms a sliding and oscillating axis for the lever F².

L is the looper-shaft, mounted to slide and rock in the bearing-blocks f f below the feed-bar F and provided at its far or rear end with two loopers l l, which coact in the ordinary manner with the two needles to form parallel rows of stitches. The near or front end of the looper-shaft passes through the yoke f² of lever F² and is then provided with a transverse operating-arm comprising a clamp l', provided with a ball l², engaged by a socket l³ on the upper end of the looper-operating lever L', the lower end of the said lever having a socket l⁴ receiving the ball d⁴, carried by the eccentrics d².

In order that the looper-shaft may have longitudinal or needle-avoiding movement in addition to the rocking or loop-taking and loop-leaving movement, I provide a transverse vertically-rocking tubular bearing L², pivoted at l⁵ to a bracket a⁹ on the inside of the post A³, and in this bearing slides the shank l⁶ of the ball l', engaged by the socket l⁸ on lever L' just below socket l³. It will be seen that as the lower end of lever L' is carried around by the wrist-pin d⁴ its upper end

will rock the looper-shaft and also oscillate on the ball l', and so reciprocate the looper-shaft. One-half of each of the sockets l³ l⁸ is formed in the removable cap l⁹, secured in place by the screw l¹⁰.

In order that the position of the wrist-pin d⁴ may be varied, it is mounted on a ring d⁹, let in an annular recess d¹⁰, formed in the face of the eccentric d² and provided with a series of slots or openings d¹¹, through certain of which pass the two attaching-screws d¹².

The take-up mechanism for the lower threads comprises the grooved cam H, the throw-off arm h, retaining-arm h', and guides h² h², as in the well-known Union Special machine. The intermittent stop device, comprising upper and lower springs I I', the lower one of which is closed against the upper by a cam I², is also the same as in said machine.

The lower threads pass from the spools 85 through the tension devices T, at the right-hand end of the gooseneck, thence forwardly through the inclined tube U to the tube U' on the upper edge of the front wall of the casing member A², thence through the two eyes in a 90 guide U², just in advance of the nipper-springs, and then between said springs to the take-up mechanism, from which the threads pass upwardly out of the casing A², through the vertically-extending tube U³, into the cylindrical bed or horn A⁴, where they pass rearwardly through guide-apertures in the bearing-blocks f f (see Fig. 2) to the loopers l l.

It will be understood that so far as many of the features of this invention are concerned I do not wish to be limited to the exact details of construction shown nor to the exact type of machine shown, whether a post or post-cylinder machine, and various modifications and changes may be made without departing from the spirit of my invention.

Having thus described my invention, what I claim as new, and desire to secure by Letters Patent, is—

1. A sewing-machine comprising a stand- 110 ard, a horizontal member projecting therefrom, a vertical member projecting from said horizontal member, a driving-shaft, and a line-shaft journaled in the horizontal mem- 115 ber and operatively connected with the driving-shaft, a feeding mechanism comprising a main feed-operating lever arranged within said vertical member, and operatively connected at its lower end with said shaft, an auxiliary lever pivoted at its upper end to 120 the main feed-operating lever, and at its lower end operatively connected to said shaft, and a looper-operating lever also arranged within said vertical member; substan- 125 tially as described.

2. A sewing-machine, comprising a casing or framework, a driving-shaft journaled there- 130 in, said casing having a horizontal and a vertical member, and a line-shaft journaled in the horizontal member and operatively

connected with the driving-shaft, a main feed-operating lever, arranged within said vertical member, and operatively connected at its lower end with said line-shaft; an auxiliary lever pivoted at its upper end to the main feed-operating lever, and at its lower end operatively connected to said line-shaft, a looper-support, and a looper-operating lever connected at its lower end also to said line-shaft and at its upper end to the looper-support, said auxiliary lever and looper-operating lever being also located within the vertical member of the casing or framework, substantially as described.

3. A sewing-machine, comprising a casing or framework having a horizontal and a vertical member, and a shaft journaled in the horizontal member, a feeding mechanism, comprising a main feed-operating lever operatively connected at its lower end to the said shaft, an auxiliary lever slidably pivoted between its ends to the vertical member, pivoted at its upper end to the main feed-operating lever, and at its lower end operatively connected to said shaft, a looper-shaft at the upper end of the vertical member, and a looper-operating lever connected at its lower end to said shaft, and at its upper end pivotally connected to the looper-supporting shaft; substantially as described.

4. A sewing-machine, comprising a casing or framework having a horizontal and a vertical member, and a shaft journaled in the horizontal member, a feeding mechanism comprising a main feed-operating lever operatively connected at its lower end to the said shaft, an auxiliary lever slidably pivoted between its ends to the vertical member, pivoted at its upper end to the main feed-operating lever, and at its lower end operatively connected to said shaft, a looper-shaft at the upper end of the vertical member, and a looper-operating lever connected at its lower end to said shaft, and at its upper end pivotally connected to the looper-supporting shaft, and having a pivotal and sliding connection below the looper-shaft, with said vertical frame member; substantially as described.

5. A sewing-machine comprising a casing or framework, having a horizontal and a vertical member, and a shaft journaled in the horizontal member, a feeding mechanism, comprising a main feed-operating lever operatively connected at its lower end to the said shaft, an auxiliary lever pivoted at its upper end to the main feed-operating lever, and at its lower end operatively connected to said shaft, a looper-shaft at the upper end of the vertical member, and a looper-operating lever connected at its lower end to said shaft, and at its upper end pivotally connected to the looper-supporting shaft; substantially as described.

6. A sewing-machine, comprising a casing or framework having a horizontal and a vertical member, and a shaft journaled in the horizontal member, a feeding mechanism, comprising a main feed-operating lever operatively connected at its lower end to the said shaft, an auxiliary lever, pivoted at its upper end to the main feed-operating lever, and at its lower end operatively connected to said shaft, a looper-shaft at the upper end of the vertical member, and a looper-operating lever connected at its lower end to said shaft, and at its upper end pivotally connected to the looper-supporting shaft, and having a pivotal and sliding connection below the looper-shaft, with said vertical frame member; substantially as described.

7. A sewing-machine comprising, a casing or framework having a horizontal and a vertical member, and a shaft journaled in the horizontal member, and provided at the base of the vertical member with two cams or eccentrics and a wrist-pin, of a main feed-operating lever connected at its lower end to one of said cams or eccentrics, an auxiliary lever slidably pivoted between its ends to vertical base member, pivoted at its upper end to the main feed-operating lever, and embracing with its lower forked or slotted end the other of said cams or eccentrics, and a looper mechanism operatively connected with the wrist-pin; substantially as described.

8. A sewing-machine, comprising a casing or framework, having a horizontal and a vertical member, and having at the base of the vertical member two cams or eccentrics, and a wrist-pin, a feeding mechanism operated by connections with the cams or eccentrics, a looper-shaft at the upper end of the vertical base member, and a looper-operating lever connected at its lower end to said wrist-pin, pivotally connected at its upper end to the looper-shaft, and having a pivoted and sliding connection below the looper-shaft, with said vertical frame member; substantially as described.

9. In a sewing-machine, a cylindrical casing or bed-plate, extending from front to rear of the machine, a feed-dog-carrying bar arranged longitudinally thereof, a sliding and oscillating looper-shaft arranged longitudinally thereof, a vertical post containing looper and feed operating lever projecting downwardly at right angles to the cylindrical casing or bed-plate, and a horizontal shaft at right angles to, but in a plane below the bed-plate or casing, means for driving it, and connections between it and said levers; substantially as described.

10. A sewing-machine comprising a casing, or framework having a horizontal and a vertical member, and a shaft journaled in the horizontal member and provided at the base of the vertical member with two cams or ec-

centrics and a wrist-pin, of a main feed-operating lever connected at its lower end to one of said cams or eccentrics, an auxiliary lever 5 slidingly pivoted between its ends to the vertical member, pivoted at its upper end to the main feed-operating lever and operatively connected at its lower end to the other of said cams or eccentrics and a looper mechan-

ism operatively connected with the wrist-pin; substantially as described.

In testimony whereof I affix my signature in presence of two witnesses.

LANSING ONDERDONK.
